UNITED STATES PATENT OFFICE.

BYRON F. WASSON, OF CLINTON, ILLINOIS.

WIRE-REEL.

No. 875,476.

Specification of Letters Patent.

Patented Dec. 31, 1907.

Application filed August 16, 1907. Serial No. 388,911.

To all whom it may concern:

Be it known that I, BYRON F. WASSON, a citizen of the United States, residing at Clinton, in the county of DeWitt and State of Illinois, have invented certain new and useful Improvements in Wire-Reels; and I do declare the following to be a full, clear, and exact description of the invention, such as will enable others skilled in the art to which

10 it appertains to make and use the same.

This invention relates to improvements in reels for supporting coils of wire.

The object of the invention is to provide a reel of this character adapted to be revolvably 15 mounted upon a wheeled supporting frame, whereby the same may be readily transported from one place to another.

A further object is to provide means whereby the reel supporting frame may be anchored to hold the reel and coil of wire at a 20 suitable inclination to permit the wire to be readily uncoiled from the reel without danger of twisting or tangling the same.

With these objects in view, the invention 25 consists of certain novel features of construction, combination and arrangements of parts as will be more fully described and particularly pointed out in the appended claims.

The accompanying drawing represents a 30 perspective view of a reel constructed and arranged in accordance with the invention.

Referring more particularly to the drawings, 1 denotes a supporting frame which is 35 preferably formed from a single angle iron bar, which is bent substantially midway between its ends to form longitudinally disposed side bars 2, and an end cross bar 3. The opposite ends of the side bars from the cross bar 3 are bent downwardly at right- 40 angles to the side bars to form stakes 4, the ends of which are beveled or cut off at an angle to form points, whereby the stakes may be readily forced into the ground.

To the side bars 2, adjacent to the end bar 45 3, are secured downwardly projecting substantially V-shaped braces 5, the lower ends of which are clipped or otherwise pivotally secured to an axle 6, on opposite ends of which are revolvably mounted supporting 50 wheels, 7. Secured to the side bars 2, midway between the connection of the upper ends of the V-shaped braces 5, is a cross bar 8, in the center of which is rigidly mounted an upwardly projecting pivot bolt, 9, on 55 which is revolvably mounted the crossed arms or bars 10 of a wire reel. The arms 10

may be formed of wood or metal and are preferably braced and strengthened by means of crossed metal plates 12, which are bolted to the upper sides thereof, as shown. 60 The bolt 9 projects above the crossed arms 10 of the reel and is threaded to receive a nut 13, to prevent the reel from riding off the bolt during the paying out of the wire.

The outer ends of the arms 10 are further 65 braced and strengthened by means of a metal hoop or band 15, which is secured to the upper sides of the same, adjacent to their outer ends. Secured to each of the arms 10 and projecting upwardly therefrom 70 at equal distances from the pivot bolt 9, are wire holding arms 16, the upper ends of which are bent or inclined outwardly as shown at 17. The arms 16 serve to hold the coil of wire in a central position upon the 75 cross bars or arms 10 of the reel. The outer ends of the side bars 2 above the stakes 4 are preferably connected together by means of a tie rod or bar 18, and between said side bars is secured a depending box or receptacle, 19, 80 in which is adapted to be placed tools or implements used in connection with the reel.

By providing the anchoring stakes 4 on one end of the side bars 2 of the supporting frame and making them shorter than the 85 distance to the reel from the ground, as herein shown, said frame may be held at an angle and firmly secured in place by driving the stakes 4 into the ground or hooking the same over some fixed object. The supporting 90 frame when thus secured will hold the reel in an inclined position, thereby greatly facilitating the paying out or unreeling of the wire therefrom.

Having thus particularly described my in- 95 vention, what I claim as new and desire to secure by Letters-Patent is:

1. A wire reel carrier, comprising an approximately U-shaped member composed of a single piece of material and having the free 100 ends of its legs bent at an angle thereto, a tie rod connecting said legs near their bent portion, a cross bar connecting said legs near their inner ends, an upwardly projecting reel-carrying pivot bolt rigidly mounted on said 105 cross bar, V-shaped braces secured at their free ends to said legs at opposite sides of said cross bar, an axle pivotally connected with said V-shaped braces, and wheels mounted at opposite ends of said axle. 110

2. A wire reel carrier, comprising an axle having supporting wheels, V-shaped braces

pivots connected at their apices with said axle near its opposite ends, an approximately U-shaped member with the legs thereof secured to the free ends of said V-shaped braces, a cross bar connecting said legs between the ends of said V-shaped braces and having reel-supporting means, the free ends of said legs being bent downwardly at an angle to form anchoring stakes, said stakes being shorter than the distance of the reel-sup-

porting means from the ground to hold the reel in an inclined position to facilitate the paying out of the wire therefrom.

In testimony whereof I have hereunto set my hand in presence of two subscribing witnesses.

BYRON F. WASSON.
